UNITED STATES PATENT OFFICE

WILFRED H. HOLLINDALE, OF DETROIT, MICHIGAN, ASSIGNOR TO TERNSTEDT MANUFACTURING COMPANY, OF DETROIT, MICHIGAN, A CORPORATION OF MICHIGAN

DESIGN FOR A DOME LIGHT OR THE LIKE FOR AN AUTOMOTIVE VEHICLE

Application filed November 6, 1929. Serial No. 33,353. Term of patent 7 years.

To all whom it may concern:

Be it known that I, WILFRED H. HOLLINDALE, a citizen of the United States, residing at 911 Artillery Street, Detroit, in the county of Wayne and State of Michigan, have invented a new, original, and ornamental Design for a Dome Light or the Like for an Automotive Vehicle, of which the following is a specification, reference being made to the accompanying drawings forming part thereof.

Fig. 1 is a plan view showing my dome light or the like for an automotive vehicle; and Fig. 2 is a side elevation of the same.

I claim:

The ornamental design for a dome light or the like for an automotive vehicle substantially as shown.

WILFRED H. HOLLINDALE.
